(57) **CLAIM**

The ornamental design for a pool cleaning device, as shown and described.

DESCRIPTION

FIG. 1 is a perspective angled front view of the pool cleaning device, which embodies my design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a perspective view thereof being partially wrapped about a pool brush head; and,

FIG. 9 is a perspective view thereof being wrapped around a pool brush head.

Portions of the drawings shown in short dashed broken lines represent stitching. Portions of the brush head in FIGS. 8 and 9 shown in long dashed broken lines form no part of the claimed design.
